(57) **CLAIM**

The ornamental design for a gooseneck lamp, as shown and described.

DESCRIPTION

FIG. 1 is a perspective view of the gooseneck lamp embodying the new design;

FIG. 2 is a right side view, the left side being a mirror image thereof;

FIG. 3 is a front view thereof;

FIG. 4 is a rear view thereof;

FIG. 5 is a top view thereof; and,

FIG. 6 is a bottom view thereof.

The broken lines shown in the drawings illustrate portions of the design and environmental structure, and form no part of the claimed design.
